UNITED STATES PATENT OFFICE.

CHARLES G. BURKE, OF RICHMOND HILL, NEW YORK.

TELEGRAPHIC SYSTEM.

SPECIFICATION forming part of Letters Patent No. 295,855, dated March 25, 1884.

Application filed December 17, 1883. (No model.)

To all whom it may concern:

Be it known that I, CHARLES G. BURKE, a citizen of the United States, residing at Richmond Hill, in the county of Queens and State 5 of New York, have invented certain new and useful Improvements in Telegraphic Systems, of which the following is a specification.

The invention more particularly relates to the class of electric telegraphs in which the 10 messages transmitted are indicated by the frequency, duration, and character of electric impulses rather than to the class in which electric currents or impulses are employed for actuating or controlling mechanism constructed 15 to print or stereotype the message in letters or words. The invention is nevertheless also applicable to the last-mentioned systems of telegraphy and telegraphic apparatus.

It has been customary to employ electric impulses of different lengths, durations, and frequency, combined in different ways, for indicating the different letters of the alphabet or other characters, and forming the words which embody the telegraphic message. These currents upon traversing the main line of a telegraphic system have heretofore been interpreted or translated into the appropriate letters and words, either by the impressions which they are caused to stereotype upon a 20 receiving-strip of paper, or directly from the movements of an armature of an electro-magnet which is caused to be vitalized thereby. The movements of the armature are rendered sensible by sound, or, as in submarine-cable 25 systems, by the movements of a ray of light reflected from a galvanometer-needle—such an instrument being substituted for the usual form of electro-magnet. In whatever manner the message is to be interpreted it has been customary to employ impulses differing in length, 30 in duration, or in polarity, which impulses, either singly or in combination, designate the different letters of the alphabet or other significant characters.

The object of this invention is to provide a system of telegraphy more rapid and less expensive in its operation than those of the character above indicated, and which is based upon a principle involving the employment of a less 45 number of separate electric currents or impulses, and which will at the same time de-

stroy or otherwise obviate the detrimental effects produced by the so-called "static" charge and discharge of the main line.

The invention consists, generally, in dividing the letters of the alphabet into separate and independent groups, preferably seven in number, designating each of the several groups by a particular electric current or combination of currents, and in indicating the individual 55 letters contained in any particular group by the interval of time elapsing after the group is designated before a succeeding group is designated, which interval agrees in units to the position of the letter in the first group. For 60 the convenience of the receiving-operator these intervals may be marked or divided into periods or units by means of a metronome, or by any suitable time-measuring device capable of 65 proper regulation.

The groups may be designated by currents of opposite polarities, currents of different strengths or of different durations, or by currents separated by different periods or intervals of time. The particular class of currents 70 to be employed will depend upon the circumstances of any particular case. The transmitting device is organized to transmit these currents in a manner appropriate to indicate the groups as well as the position of the letters in 75 the group. This is accomplished by separating each succeeding group from the preceding group by an interval of appropriate duration for indicating the letter. The receiving-operator recognizes the groups, as they are successively denoted, by the effects produced by 80 the currents, and the letters by the intervals occurring between the group-indicating currents or combination of currents.

When electric currents of different polarities are to be used—a method which is very efficient in submarine cables and other long lines of telegraph—the transmitting device 85 may be conveniently organized to cause a rotating circuit-closing arm to pass successively beneath the extremities of two rows of keys arranged in concentric circles, the individual keys in the two rows being placed in the same radial lines. The two series are respectively connected with the positive and the negative 90 poles of two batteries or other convenient source of electricity, and a current of the cor-

responding character will be transmitted when a key in either series is projected into the path of the circuit-closing arm. Means are provided for regulating the rapidity with which 5 the circuit-controlling arm shall revolve, and the period intervening between the passage of the arm from one pair of keys to the next succeeding pair is the same throughout its entire revolution. At the receiving-station an 10 interpreting device of any suitable character—such, for instance, as a reflecting-galvanometer—is caused to be actuated by the positive and negative currents, and casts a reflected ray of light in one direction or the other, according to the polarity of the current. 15

Any convenient device—such, for instance, as a metronome regulated to beat once for each pair of keys passed by the circuit-closing arm of the transmitter—may be employed for 20 the purpose of assisting the receiving-operator in measuring the units of time intervening between the successive groups of signals. A suitable device for enabling the receiving-operator to manually record the letters as they 25 are successively indicated is also located at the receiving-station, and the reflected ray of light is preferably thrown directly upon the key-board of such an instrument.

Other obvious methods of designating and 30 interpreting the groups may be used—as, for instance, currents or impulses of a given strength may be substituted for the positive impulses, and of an increased or of a diminished strength for the negative impulses—for 35 the purpose of determining the groups, and these may be interpreted with the aid of two telegraphic sounders adjusted to respond to the respective current strengths. Again, it may be found convenient in some instances to employ 40 currents of two different durations—such as are employed for denoting the “dots” and “dashes” of the Morse telegraphic code. These group-designating currents may be received directly upon chemically-prepared paper, and subsequently interpreted at the convenience of the receiving-operator. 45

It is evident that any of the well-known classes of automatic transmitting devices may be employed—as, for instance, the messages 50 may be perforated or stenciled in a strip of paper and afterward passed beneath a suitable transmitting-stylus.

The letter-groups into which the alphabet is divided are preferably seven in number. 55 The first group, when positive and negative designating-impulses are employed, is designated by a single positive impulse, and the second by a single negative impulse. The third group is designated by a positive followed by a negative impulse, and the fourth by a negative followed by a positive impulse. Two positive with an intervening negative impulse signifies the fifth group, and two negative with an intervening positive impulse indicates the sixth group. The seventh group is denoted by two positive and two negative im-

pulses alternating with each other. The groups into which it is desirable to divide the letters of the alphabet in practice are dependent upon the frequency with which they are 70 employed in ordinary composition, for it will be evident that it is desirable to designate the groups containing the letters which are most frequently employed by means of the briefer signals. For this purpose the letters are preferably arranged in the following groups, the numerals referring to the number of the group in each instance: I, E A I O; II, N U T S; III, C H P L; IV, B Y R D; V, W M F G; VI, K G Q V; VII, X Z. 75

The letters of the alphabet having been thus divided into groups, it will be seen that each letter may be further designated, according to the position which it occupies in its group. Thus “E” is the first, “A” the second, “I” 80 the third, and “O” the fourth letter in the first group. The interval of time, therefore, which elapses after any particular group has been designated by its signal before a succeeding group-signal is received indicates to 85 the receiving-operator some particular letter in that group.

Considering that the letters are to be designated by intervals or units of time elapsing after the group-signal has been transmitted, 90 and that these units are designated by a metronome, the following tabulated form will serve to illustrate, first, the group-signals, and, second, the units of time or beats of the metronome by means of which the letters are indicated: 100

IV.	
— . e	— + . b
— . . a	— + . . y
— . . . i	— + . . . r
— . . . . o	— + ... d
II.	
— . n	+ — + . w
— . . u	+ — + . . m
— . . . t	+ — + . . . f
— . . . . s	+ — + ... g
III.	
+ — . e	+ + — . k
+ — . . h	+ + — . . g
+ — . . . p	+ + — . . . q
+ — l	+ + — v
VI.	
+ —	+ + — . . . . .
VII.	
+ — + — . x	
+ — + — . . z	

It will be understood thus that if it is desired to transmit the word “ink” a single positive impulse is transmitted, designating the first group. This is followed, after three units of time, by a single negative impulse. The three units indicate the third letter of the first group designated—that is to say, the letter “i”—and at the same time the single nega- 125

tive impulse designates the second group. A unit of time having elapsed, two negative with an intervening positive impulse would at the same time point out the first letter, "n," in 5 the second group, and designate the sixth group as being the one from which the succeeding letter is to be chosen. A single unit of time intervening before another current or combination of currents would then designate 10 the letter "k."

Any suitable combination of currents may be employed for indicating the marks of punctuation and spaces—such, for instance, as two positive currents for a period and two negative currents for a space.

It will be observed that the pulsations employed for indicating the groups are each composed either of a single current or of a series of currents of alternating polarity. Such a 20 combination of currents effectually prevents any detrimental results which have heretofore been encountered from a static condition of the main line or cable.

It is well known that the effect of a current 25 of opposite polarity succeeding any given current is to neutralize the static discharge which otherwise succeeds the interruption of the preceding current. The time which lapses between the indication of any two successive 30 groups of letters is sufficient to allow the static discharge of the last current employed to take place before the next succeeding group is indicated.

When it is desired to employ electric currents of different strengths for furnishing the 35 group-indicating signals, the same system of group-divisions is applied, the positive current being replaced by currents of a given strength, and the negative currents by currents 40 of a greater or of less strength. The currents of different strengths may be of the same or of opposite polarity, as desired. Likewise the substitution of currents of different durations may also be effected by assigning a current of 45 a given duration in place of a positive current, and a current of another and distinctive duration in place of a negative current wherever those currents occur in the system first described.

50 In the accompanying drawings, Figure 1 is a diagram illustrating the method of carrying the invention into execution, in connection with an organization of apparatus especially adapted to submarine-cable systems; and Fig. 2 illustrates certain details in the construction of the 55 transmitting device. Figs. 1^a, 1^b, and 3 illustrate the construction of the time-measuring instrument. Fig. 4 is a diagram illustrating the invention as applied to a system in which 60 currents of different strengths are employed.

Referring to Figs. 1, 1^a, 1^b, 2, and 3, A represents a transmitting key-board, which is divided into two insulated series, B' B², of transmitting keys. These series are respectively 65 connected with the positive and with the negative poles of two batteries, E' and E², by con-

ductors 1 and 2. The remaining poles of these batteries are connected with the earth by a conductor, 3. The keys in the two rows B' and B² are arranged in the same radial lines, 70 and the distance between the successive keys in each row is the same throughout the circular series. Beneath the keys extends a circuit-closing arm, F, which is placed in electrical connection with a main line or cable, L. 75 The circuit-closing arm F is provided with suitable means, preferably an electric motor, for causing it to revolve at a determinate rate beneath the lower extremities of the circuit-closing keys. Each key is constructed, as 80 shown in Fig. 2, with a beveled or rounded extremity, which is normally held out of the path of the circuit-closing arm F by means of a spring entering an annular groove or notch, f². Each key may, however, be pressed downward, so that its lower extremity will project into the path of the circuit-closing arm F. This arm, by striking against the key during its revolution, not only completes the electrical connections of one or the other battery, E' or 85 E², with the main line L, accordingly as the depressed key is in the series B' or B², but it also serves to force the key upward again into its normal position without arresting the movement of the arm. The currents which 90 may thus be transmitted by means of the key-board to the main line are caused at the receiving-station to traverse the actuating-coils of a reflecting-galvanometer, G, of well-known construction. The movements of the galvanometer-needle are rendered apparent by 95 means of the movements thus imparted to a ray of light falling upon a mirror, g, which is supported upon the arbor of the galvanometer-needle. Such a ray of light is, for convenience, reflected upon a key-board, herein-after described, and is bent toward the left hand or toward the right, accordingly as the 100 actuating current or impulse is of positive or negative polarity.

105 The galvanometer shown in the drawings consists of a permanent magnet, g', between the poles of which is delicately suspended a needle, g². Surrounding the needle is a coil of insulated wire, g³, the convolutions of which 110 extend in the direction parallel with the normal direction of the needle g². A current of a given polarity traversing the coils g³ serves to deflect this needle in one direction, and a current of opposite polarity deflects the same 115 in the opposite direction. The ray reflected by the mirror g is derived from a flame, g⁴, and is preferably cast, as before stated, upon a key-board, P, though it may be received upon an independent screen. By the movements of this reflected ray the polarities of the 120 currents transmitted are readily determined by the operator. The receiving-operator may therefore readily determine the particular group of letters at any time selected by the 125 transmitting-operator, and by measuring the intervals which elapse between the successive 130

groups he determines the particular letters selected. By means of a metronome the intervals may be conveniently divided into units equal to the time occupied by the circuit-closing arm in passing from one pair of keys in the transmitter to the next succeeding pair. Such a device is shown at H, Fig. 1^b, and it may be of any convenient construction. In the construction shown a revolving wheel, h', is driven at a constant rate by means of a weight, h². From the periphery of this wheel extends a series of equidistant radial pins, h³, which are successively engaged by means of a vibrating escapement, h⁴. This escapement consists of two teeth, h⁵ and h⁶, respectively, facing each other, but in different planes, and carried upon one arm of the vibrating pendulum h⁷. Sufficient distance intervenes between the planes in which the edges of the teeth h⁵ and h⁶ are placed to permit the passage of the teeth or pins h³ between them when the pendulum is vibrated laterally. Upon the pendulum-rod are carried one or more weights, h⁸ and h⁹, which may be adjusted for modifying the rapidity with which it will be vibrated under the influence of the wheel h'. The sound obtained by the striking of the successive pins against the teeth of the escapement is employed for measuring the successive beats, and thus the units of time into which the intervals are divided. There is also placed at the receiving-station a recording-instrument, which may consist of any suitable form of type-writer. The key-board of this instrument is preferably arranged as indicated at P. Considering the line p' to be the center of the board, the keys in the lower left-hand line, commencing at the left extreme, are designed to represent the letters contained in the first group—namely, "e a i o." The line above represents the letters in the third group—namely, "c h p l." Likewise the line next above represents the letters "w m f g," and the two keys in the upper line represent "x z." The keys arranged upon the right-hand side of the central line indicate in the same manner the letters contained in the right-hand groups. It will be seen that the groups comprised upon the two sides of the board are arranged accordingly as the first impulse of current employed for representing the group is a positive current or a negative current, those represented by a positive primal current being upon the left-hand side of the board, and those by a negative primal current upon the right-hand side. In the central line two keys, p' and p², are placed, which are respectively designed to represent a space and a period.

At a convenient place upon the key-board P is formed a scale or plane surface, P', upon which the ray of light from the galvanometer is reflected. This construction renders it convenient for the operator to watch the movements of the ray while he is operating the keys. An independent screen may, however, be substituted for this last-named construction.

In practice, also, the operator may in some instances dispense with the mirror and reflected ray of light and determine the groups by watching the movements of the galvanometer-needle, for it will be readily understood that it is not necessary to observe the degree of movement of the needle, but merely its direction.

Thus far the description of the drawings has been given in connection with the use of electric currents distinguished from each other by their polarity. A method of adapting the invention to apparatus organized to employ electric currents of different strengths will be described in connection with Fig. 4. In this organization a single battery, E¹, is substituted for the batteries E' and E². One pole—say the negative—is connected with the earth by a conductor, 4, and the remaining pole is provided with two conductors, 5 and 6, respectively leading to the series B' and B² of transmitting-keys. In one of these conductors, 6, is included an artificial resistance, R, adapted to reduce the currents which are transmitted to line by means of the keys B². The two classes of current thus obtained may, for convenience, be considered as having the one double the strength of the other. At the receiving-station these currents are caused to actuate one or the other of two relays, S' and S², which are respectively adjusted to respond to currents transmitted through the agency of the keys B' and B². These relays may be of any well-known form. In the drawings, the relay S' is represented as an ordinary electro-magnet, with an armature-lever, s', which is adjusted to respond to electric currents of the strength transmitted by the series of keys B', but not of the strength transmitted by the series B². The connections of a local circuit, including a sounder, T', are designed to be completed by this relay, when the armature s' is against its front contact-stop. The relay S² is provided with an armature-lever, s², and a supplemental lever, s³, against which it strikes when attracted by its electro-magnet. The armature-lever s' is adjusted to respond to currents of the strength transmitted by the action of the series of keys B². When, however, a current of the strength transmitted by the keys B' traverses the main line, the armature is attracted with sufficient force to actuate the supplemental lever s³ also, and to impel it away from its back contact-stop, s⁴. A local circuit, including a sounder, T², has its terminals respectively connected with the armature-lever s² and the stop s⁴. The connections of this circuit will therefore be completed only through the influence of currents transmitted by the series of keys B².

The two sounders T and T² are respectively placed near the opposite extremities of the receiving key-board P, and the receiving-operator will be able to readily determine the group-signals from the action of these sounders in the

same manner as described with reference to Figs. 1, 1^a, 1^b, 2, and 3.

The theory of the invention may be still further carried out by substituting for the currents of opposite polarity, or the currents of different strengths, currents of other distinctive characteristics.

It is evident that numerals may be added to the series of letters and indicated by group signals in the same manner as described, and that the combinations of currents may be indefinitely extended.

I claim as my invention—

1. The hereinbefore-described method of telegraphy, which consists in distinguishing different groups of characters by an electric current, impulse, or combination of electric currents or impulses, and the individual letters contained in such groups by distinctive intervals of time occurring after the group-signal has been given and before a succeeding signal is commenced.

2. The hereinbefore-described method of telegraphically indicating different characters of a series which consists in dividing such series into arbitrary groups, designating each of the several groups by means of electric currents possessing particular characteristics, and indicating the individual letters in the several groups by different intervals of time succeeding the group-designating currents.

3. The hereinbefore-described method of telegraphy which consists in indicating different groups of letters or characters by electric currents of distinguishing characteristics, and indicating the individual characters by different numbers of units of time elapsing after such groups are indicated, substantially as described.

4. The hereinbefore-described method of telegraphy, which consists in designating each particular group of letters by the transmission of electric currents or impulses, and each individual letter in such group by the interval elapsing before the transmission of a succeeding current or impulse.

5. The hereinbefore-described method of indicating the individual characters of a series, which consists in indicating the groups into

which said series is divided by electric currents, and assigning to each character in each group a distinctive period of time by the occurrence of which, after the group has been indicated, that character is designated.

6. The hereinbefore-described method of indicating the different characters in a series, which consists in dividing such series into groups, designating each of the different groups by a characteristic signal, and indicating the individual characters in such groups by the measurements of a metronome.

7. The hereinbefore-described method of transmitting telegraphic messages, which consists in indicating different groups of character-recording keys, corresponding to the characters which constitute an embodiment of such message, by predetermined electric signals, and indicating the particular recording-key in a designated group by the interval occurring after such group has been designated before another signal is commenced.

8. The hereinbefore-described method of indicating the different keys of a character-recording key-board which correspond to the characters embodying a telegraphic message, which consists in indicating the side of such board upon which such keys are located by primal signals, the particular line of keys containing such keys by the same primal signal, or a combination therewith of other signal or signals, and the particular key in such line by the units of time measuring the intervals between the signals or combination of signals.

9. The hereinbefore-described method of indicating the different characters contained in a series, which consists in designating different groups of said series by the movements of a reflected ray of light, and indicating the different characters contained in such groups by the period during which the direction of such ray of light is unchanged.

In testimony whereof I have hereunto subscribed my name this 15th day of December, A. D. 1883.

CHARLES G. BURKE.
